BOBBIN

Joseph W. Bourassa, Greene, Maine, assignor, by
mesne assignments, to himself and Alphonse
B. Bourassa, as tenants by the entirety

Application March 24, 1950, Serial No. 151,739

1 Claim. (Cl. 242—120)

This invention relates to an improved bobbin for use especially in the roving process where-in it is customary to employ a bobbin having a wooden barrel section supported in a position to be contacted by a metal dog on a spindle gear in driving relation therewith.

In a roving frame the sliver body built up on the bobbins is very large. A great deal of difficulty is experienced with the wrecking, or partial break down, of the base section of the bobbin in service due to its continued impact against the metal dog on the spindle gear. It frequently happens that the bobbin will split throughout its entire length due to this action, and it is also common to have the base so worn after a short period of service that the contact with the spindle gear is loose, and such looseness results in the production of unsatisfactory yarns. Various expedients have been suggested to prevent this wear, including reinforcing rings secured about the bottom of the base element, as well as sheet metal armor crimped around the bottom edge of the base, none of which are entirely satisfactory from a service standpoint.

The present invention is concerned with the problem indicated and seeks to devise a reinforced bobbin construction having a specially formed base section which will resist wear and prevent wrecking, or other damage, to the bobbin body and, at the same time, eliminate the need for metal reinforcing members. It is also an object of the invention to provide a bobbin construction which is capable of long operation; which is relatively cheap and efficient to manufacture; and which will provide for more satisfactory operation from a safety standpoint.

These and other objects and novel features will be more fully understood and appreciated from the following description of a preferred embodiment of the invention selected for purposes of illustration and shown in the accompanying drawings, in which

Fig. 1 is a view in side elevation illustrating the improved bobbin of the invention, including an annular base element indicated as being in engagement with the metal dog of a spindle driving gear;

Fig. 2 is a fragmentary enlarged elevational view partly broken away to show in cross-section the lower portion of the bobbin barrel with the annular base element removed;

Fig. 3 is another elevational view of the annular base element with a part of the base element being shown in cross-section;

Fig. 4 is a bottom plan view of the base element shown in Fig. 3; and

Fig. 5 is an enlarged vertical cross-sectional view showing the base element secured in threaded relation to a wooden barrel section of the bobbin.

5. I have found that one solution to the above indicated problem resides in utilizing a relatively hard plastic body, such as a vulcanized fiber, to constitute the base section of a bobbin. More specifically, I find that certain forms of vulcanized fiber which are characterized by unusually high degrees of durability and resistance to shock and wear may be combined with a wooden barrel section of a bobbin by means of a novel threaded and jointed construction to provide a reinforced bobbin structure which will adequately resist the wear and stresses of bobbin use. In the structure shown in the drawings, numeral 10 denotes a cylindrical barrel portion of the usual size employed in roving frames and preferably constructed of wood. At its lower portion the barrel 10 curves outwardly to form an enlarged annular rim 12, as shown in Figs. 2 and 5. The rim 12 at its outer periphery is constructed with a cylindrical surface 14 and extending between this cylindrical surface 14 and the normal peripheral surface 10 of the bobbin is an annular concaved surface 18. The lower side of the rim 12 is relieved to provide a radially extending annular surface 20 and projecting downwardly from the surface 20 is a reduced neck 22 which is provided with threads 24. The neck portion terminates in flat bottom edges 26, as shown in Figs. 2 and 5.

In accordance with the invention, I combine with the barrel construction described above an annular base element 28 which is formed of a substance referred to as "vulcanized fiber." This product consists essentially of cellulosic fibers, usually cotton cellulose paper, chemically converted to a new structure by means of treatment with agents, such as zinc chloride, sulfuric acid, and the like.

I find that while several types of fiber are not satisfactory, there is at least one type of vulcanized fiber suitable for use in accordance with the invention. This suitable form of material comprises the type of vulcanized fiber commonly referred to as "bone fiber," characterized by a relatively high density and toughness, such as is exemplified by a fiber with a tensile strength of at least 8500 lbs. per square inch measured in one dimension in thicknesses up to an eighth of an inch; and also characterized by a compressive strength of 3000 lbs. per square inch in all thicknesses.

55 It is intended that a type of vulcanized fiber

having properties adhering pretty closely to the above described properties, are to be employed in forming the base portion of the bobbin of the invention.

The base element is designed to fit around each of the specially formed barrel surfaces described above and thus provides for a novel jointed construction. The base element 28 is provided with internal threads 32 and these threads secure the annular base element around the neck portion 22 in such threaded relation that a leverage applied to a strand of yarn which is being wound on the bobbin tends to tighten the threaded engagement of the base element on the bobbin. In addition, an adhesive material 36 is preferably employed 15 to hold the barrel and base in fixed relation to one another.

The base element is also constructed with means for forming jointed sections above and below the threaded neck. It includes an annular shoulder 30 which bears against the bottom edge 26 of the neck in a fully threaded position of the base element. A second annular shoulder 34, offset from shoulder 30, is also provided in the base element in a position to abut against the surface 20 of the rim 12. At its uppermost portions the annular base element 28 includes a lip 40 which is adapted to encircle the cylindrical surface 14 of the rim 12. The external periphery of the lip 40 is of a generally convex shape and is so chosen that it meets with the concave surface 18 and the two surfaces cooperate to form a reversely curved shoulder of relatively smooth contour for proper handling of yarn wound thereagainst.

The combined threaded and jointed construction of the annular base element and barrel extremity provides a very rugged bobbin construction which, it is found, is quite capable of undergoing the shock and wear attendant upon operation in a roving frame. The construction described is well suited to resisting the wear resulting from contact with a metal dog 44 driven by a spindle gear 42 and engaged in slots 46 in the bottom of the annular base element 28. It will be observed that two distinct bearing surfaces offset from one another are provided in a position to resist impact forces directed axially of the bobbin and base element construction. With this double bearing construction is combined the intermediate threaded relationship for resisting separation of the two members from one another when subjected to rotative movement, the adhesive material serving to aid in securing the two parts together.

It will also be observed that with the upper 55

shoulder bearing and rim construction there is achieved a smooth reversely curved thread handling surface composed partly by the wooden barrel and partly by the annular base element. With the arrangement described it has been found that no metal crimping or reinforcing is necessary and that splitting or splintering of the wooden barrel sections is completely eliminated and an exceptionally long bobbin life may be realized.

Having thus described my invention, what I desire to claim as new is:

An improved shock resistant bobbin construction for use in the roving process and similar textile operations, said bobbin construction including a cylindrical barrel section of wood and an annular reinforced vulcanized fiber base secured at the lower end of the barrel section and having a downwardly facing slotted portion at its bottom face adapted to be located in driving relationship with the metal dog of a spindle gear, said barrel section being formed with a reduced lower end portion presenting a bottom radially extending shoulder, a second radially extending shoulder having its face parallel to the face of the first shoulder located above and in spaced relation to the bottom radially extending shoulder both vertically and laterally, a threaded portion occurring between the upper and lower shoulders, a third radially extending shoulder spaced vertically and laterally of the second shoulder, said annular reinforcing base being constructed with complementary threads and radially extending shoulder portions, the radially extending shoulder portions of the annular base in a fully threaded position solidly bearing against corresponding shoulder portions of the barrel section at points above and below the threads to provide a shock resistant barrel joint, and all abutting pairs of shoulders being spaced inwardly from the outer wall of the annular base and below the top thereof.

JOSEPH W. BOURASSA.
